(57) **CLAIM**

The ornamental design of a winglet for a side rocker panel of an automobile, as shown and described.

DESCRIPTION

FIG. 1 is an isometric view of a winglet for a side rocker panel of an automobile showing my new design;

FIG. 2 is a front, elevation view of the winglet for a side rocker panel of an automobile of FIG. 1;

FIG. 3 is a back, elevation view of the winglet for a side rocker panel of an automobile of FIG. 1;

FIG. 4 is a right side elevation view of the winglet for a side rocker panel of an automobile of FIG. 1;

FIG. 5 is a left side elevation view of the winglet for a side rocker panel of an automobile of FIG. 1;

FIG. 6 is a top view of the winglet for a side rocker panel of an automobile of FIG. 1; and,

FIG. 7 is a bottom view of the winglet for a side rocker panel of an automobile of FIG. 1.

The features shown in broken lines in the drawing depict portions of the design that form no part of the claimed design.
